UNITED STATES PATENT OFFICE

2,074,783

CIGARETTE MACHINE

William Frederick Maitland Edwards, London, England, assignor to Filter Tips Limited, London, England, a British company

Application November 7, 1934, Serial No. 751,952
In Great Britain November 9, 1933

9 Claims. (Cl. 131—43)

This invention relates to cigarettes and is concerned with improvements in apparatus for the manufacture on the continuous rod principle of cigarettes having filtering insertions or tubes at 5 the mouthpiece end or at an intermediate position or of cigarettes having hollow mouthpieces into which filter tips or like insertions may be subsequently applied.

According to the present invention the improved apparatus for manufacturing cigarettes of the kind referred to comprises means for severing a continuous tobacco filling into lengths, reciprocatable gripping means adapted to engage the cut lengths successively and move the same 10 bodily forward to provide intermediate spaces between the lengths, and paper tube-forming means arranged so that the spaced lengths are delivered onto the paper strip and enclosed therein. The cutting means preferably is reciprocatable so that the continuous tobacco filling may be severed without interruption of its continuous 15 forward movement.

The invention furthermore includes apparatus comprising means for gripping the continuously 20 moving filling while it is cut into lengths, said gripping means being adapted to effect accelerated forward movement of the cut lengths to form spaces therebetween and means for applying a continuous paper strip so as to form a tube 25 enclosing the spaced lengths of filling. Pairs of grippers may be arranged to engage the filling at 30 both sides of the cutting means. Any suitable means may be provided for applying intermediate filtering or other insertions into the spaces between the lengths before the continuous tube is 35 formed therearound.

The invention is hereinafter described by way of example with reference to the accompanying diagrammatic drawings, in which:

40 Figure 1 is a sectional end elevation illustrating one construction of apparatus in accordance with the invention;

45 Fig. 2 is a view similar to Fig. 1 illustrating the manner in which the grippers engage the filling; Fig. 3 is a part sectional side elevation corresponding to Fig. 2; and

50 Fig. 4 is a view similar to Fig. 3 illustrating the manner in which the space is formed by advancing the cut-off length of filling.

55 Fig. 5 is a fragmentary elevational view of the mechanism for shifting the carriages.

Fig. 6 is an end view of the mechanism shown in Fig. 5.

Fig. 7 is a fragmentary view of the connection 55 between shaft 17 and its driving mechanism.

Fig. 8 is a sectional view taken on line 8—8 of Fig. 7.

In carrying the invention into effect, the tobacco filling 1, preferably while moving along a trough-like guide 2c upon an endless band 2, 5 is operated on by reciprocatable gripping devices comprising pairs of jaws 13, 14 and 15, 16 adapted and operated so as to be capable of insertion between the tobacco filling and the band.

The jaws 13, 14 and 15, 16 are carried respectively by arms 13a, 14a and 15a, 16a which are connected by links 13b, 14b and 15b, 16b respectively to pivots of rollers 13c, 15c, the pivots connecting the pairs of arms and links being adapted for engagement by tension springs 13d, 15d respectively. The arms 13a, 14a are pivoted on a spindle 17 and the arms 15a, 16a on a spindle 18, such spindles 17, 18 being carried respectively by carriages 19, 20 slidable on parallel rods 21 and operated through rods 22, 23 by 20 suitable cam mechanism. As shown in Figs. 5 and 6, rods 22 and 23 are connected by links 30 and 31 with levers 32 and 33, respectively. Levers 32 and 33 are provided with rollers 34 and 35, which engage cams 36 and 37, which serve to 25 rock levers 32 and 33 about fulcrum 38. Cams 36 and 37 are rotated by a shaft 39, which is driven by a source of power (not shown). It will be noted that cams 36 and 37 are constructed to impart an acceleration to the movement of rod 22 30 relative to rod 23 as the two rods are being shifted. The specific form of means for imparting acceleration to the movement of rod 22 relative to rod 23 as the two rods are being shifted 35 is not a novel feature in this case, the same being merely a conventional form of such accelerating means. A lever 24 having a lateral extension 24a co-operating with the rollers 13c, 15c is pivoted at 24c and is provided at its rear end with a roller 24b engaging with a 40 bar 25 which is adapted to be raised and lowered through suitable cam mechanism. A rotatable cutter 26 is mounted on the spindle 17 which is rotated by suitable mechanism through a telescopic connection. For instance, 45 shaft 17 may be squared as shown at 17' and passed through a square opening 40 in a spindle 41 on which a gear 42 is mounted. Spindle 41 is carried in a stationary bearing 43 and as the carriage 19 is shifted the shaft 17' slides through 50 the opening in spindle 41.

At the commencement of the forward movement of the carriages 19, 20 the latter move in unison and by upward movement of the bar 25 the jaws 13, 14 and 15, 16 are caused to close 55

together, as illustrated in Figure 2, so as to engage the filling and subject the same to compression, the jaws also preferably acting to lift the filling from the paper strip or band while the cutter 26 severs the filling. After the cutting operation the forward movement of the carriage 19 is accelerated so as to carry the cut length of filling bodily forward without exerting an axial compression thereon, thereby forming a space, as illustrated in Figure 4. The bar 25 is then lowered so as to permit the jaws to open out into the position shown in Figure 1 in which the filling is released. The carriages 19, 20 then return to the initial position. The cutter 26 may be operated in such manner that after the cutting operation it remains in engagement behind the cut length of filling. Alternatively, the forward movement of the cut length of filling may be effected by a separate blade after the jaws 13, 14 have been actuated to release the cut length.

In a further modification the gripping jaws 15, 16 may be dispensed with, in which case the cutter or a separate blade may be adapted to remain in engagement with the cut end of the continuous filling while the cut length is moved forward as before described. The paper strip (not shown) moves at a constant speed which is suitably greater than the speed of feed of the continuous filling and is guided over a roller so as to receive the filling at any suitable position in relation to the cutting and space forming means.

The insertions may be applied in the spaces before the paper strip is formed into a continuous tube or the paper strip may be wrapped around the spaced lengths of filling and subsequently cut off to provide cigarettes having hollow mouthpieces into which insertions may be applied subsequently.

40 The invention is applicable for the production of cigarettes having any desired form of tip or mouthpiece or intermediate insertion. If desired, the insertions may be in the form of wads or tufts of cottonwool or similar material, or may consist wholly or in part of tobacco, in which case cigarettes containing tobacco of two different kinds or characteristics may be readily produced.

The invention is also applicable for producing composite cigarettes having an insertion at an intermediate position in the length of the cigarette.

It will be understood that the invention is not limited to the particular embodiments hereinbefore described. For instance, although it is preferred to effect the formation of the spaces between the lengths of filling without interrupting the continuous forward movement thereof, the continuous feed movement of the filling may be interrupted while the cutting and/or space-forming operations are carried out.

What I claim is:—

1. Apparatus for producing cigarettes of the kind referred to, comprising means for severing a continuous tobacco filling into lengths, and reciprocatable gripping means adapted to engage the cut lengths and to move the same bodily forward to provide intermediate spaces between the lengths.

2. Apparatus for producing cigarettes of the kind referred to, comprising means for gripping a continuously moving tobacco filling while it is cut into lengths, and means for shifting said

gripping means to effect accelerated forward movement of the cut lengths to form spaces therebetween.

3. Apparatus according to claim 2, wherein pairs of grippers are arranged to engage the filling at both sides of the cutting means.

4. In a machine of the character described, a trough for supporting a moving rod of tobacco filling for cigarettes, a cutter for severing said filling into lengths, means for reciprocating said cutter to cause it to move with said filling during the severing operation, and gripping means adapted to move the cut length of filling in advance of the moving rod to provide a space between the cut length and moving rod.

5. In a cigarette machine, a trough for supporting a moving rod of tobacco filling for cigarettes, a carriage reciprocable in a direction parallel to the direction of movement of said rod, a cutter mounted on said carriage, means for operating said cutter to sever a length from said rod while the carriage is moving with said rod, and means for accelerating the movement of said severed length to provide a space between the same and said rod.

6. In a cigarette machine, a movable trough-like member for supporting a moving rod of tobacco filling for cigarettes, a carriage reciprocable in a direction parallel to the direction of movement of said rod, a cutter mounted on said carriage, means for operating said cutter to sever a length from said rod while the carriage is moving with said rod, and means for accelerating the movement of said severed length to provide a space between the same and said rod.

7. In a cigarette machine, a trough for supporting a moving rod of tobacco filling for cigarettes, a carriage reciprocable in a direction parallel to the direction of movement of said rod, a cutter mounted on said carriage, means for operating said cutter to sever a length from said rod while the carriage is moving with said rod, and gripping means for accelerating the movement of said severed length to provide a space between the same and said rod.

8. In a cigarette machine, a movable member for supporting a moving rod of tobacco filling for cigarettes, a carriage reciprocable in a direction parallel to the direction of movement of said rod, means on said carriage for lifting a portion of said rod from the moving member, means for severing the lifted portion of the rod, and means for shifting said severed portion of said rod in advance of the remainder of the rod to provide a space therebetween.

9. In a cigarette machine, a movable member for supporting a moving rod of tobacco filling for cigarettes, a carriage reciprocable in a direction parallel to the direction of movement of said rod, means on said carriage for lifting a portion of said rod from the moving member, a second carriage reciprocable with and relative to the aforementioned carriage, a cutter carried by said second carriage, means for operating said cutter to sever a length of rod from said lifted portion thereof, means on said second carriage for gripping the severed length of rod, and means for shifting said second carriage relative to the first carriage to move the severed length in advance of the moving rod to provide a space therebetween.

WILLIAM FREDERICK MAITLAND
EDWARDS.
